UNITED STATES PATENT OFFICE.

WILLIARD A. HALLENBECK, OF HUDSON, NEW YORK.

PUZZLE.

SPECIFICATION forming part of Letters Patent No. 602,219, dated April 12, 1898.

Application filed August 17, 1897. Serial No. 648,484. (No model.)

To all whom it may concern:

Be it known that I, WILLIARD A. HALLENBECK, a citizen of the United States, residing at Hudson, in the county of Columbia and State of New York, have invented a certain Improvement in Puzzles, of which the following is a specification.

My invention relates to a new and amusing puzzle; and it consists of three trays, one arranged above the other, each of less diameter than the one next below, the two upper trays having openings cut in their rims, whereby the balls which are utilized in solving the puzzle are permitted to pass from one tray to the other until finally reaching the lower tray, after which they may be so manipulated as to be caused to occupy the stalls located in said tray.

My invention is illustrated in the accompanying drawing in perspective form, and in this drawing A represents the lower tray, in which is located the block B, having formed therein the stalls C, which are here shown as four in number. From the upper surface of this block projects a post D, which supports the second tray E, and in turn a post F projects upward from the second tray and supports the top tray G. The several parts are preferably held together by a rod H, which passes through the trays and posts, as well as the block B, and has threaded upon its upper end a nut I, while its lower end is provided with a head and washer. (Not shown.)

The tray G has an opening J formed in its rim, while the tray E also has an opening K formed in its rim.

The object of the puzzle is to place the four balls L in the upper tray and by oscillating and otherwise manipulating the tray cause said balls one by one to first pass from the tray G to the tray E and from thence to the tray A, after which they are to be arranged within the stalls C, which is the solution of the puzzle.

It will be seen that much skill and patience as well as steadiness of nerve are required for the accomplishment of the result aimed at, and this will not only interestingly occupy considerable time, but will also tend to train a person's sensibility in balancing and steady- ing the movements of the hand under control of the eye, and when the puzzle has been once solved it will be nearly as difficult of

re-solution as at first, thus affording endless amusement and exercising a certain amount 55 of educational effect upon both young and old.

When the trays and block are made of pasteboard, the cost of producing my improved puzzle is very small, which will add to its salability by placing it in the reach of 60 all; but I do not wish to limit myself to the material from which the device may be made, as this may be varied without departing from the spirit of my invention.

While I have shown the rod for holding the 65 several parts of the device in place as being threaded upon its upper end and having the nut run thereon, it is obvious that the head of this rod may be so located, while the nut is placed upon the lower end of the rod and 70 countersunk within the tray or block.

Having thus fully described my invention, what I claim is—

1. A puzzle, consisting of three trays, one arranged above the other, each of less diameter than the one next beneath, the two upper trays having openings cut in their rims, and a block having stalls therein located in the lower tray, as specified. 75

2. As a new article of manufacture, a puzzle, consisting of three circular trays, each of less diameter than the one next beneath, the two trays having openings cut in their rims, a block having stalls formed therein located in the lower tray, and posts upon which the 85 trays are supported, all arranged substantially as and for the purpose set forth. 80

3. In combination, three circular trays arranged one above the other, each of less diameter than the one next beneath, the two 90 upper trays having openings formed in their rims, a block having stalls formed therein located in the bottom tray, posts D and F for supporting the upper trays, a rod passed through the several members of the device for holding them in place, and four balls to be placed in the upper tray and transferred one by one to the stalls in the lower tray, as specified. 95

In testimony whereof I have hereunto affixed my signature in the presence of two sub- 100 scribing witnesses.

WILLIARD A. HALLENBECK.
